UNITED STATES PATENT OFFICE.

ROBERT H. McCUNE, OF ROSWELL, NEW MEXICO.

PORTABLE FOLDING BED.

1,303,487.

Specification of Letters Patent.

Patented May 13, 1919.

Application filed November 11, 1918. Serial No. 262,007.

To all whom it may concern:

Be it known that I, ROBERT H. McCUNE, a citizen of the United States, and a resident of Roswell, in the county of Chaves and 5 State of New Mexico, have invented a certain new and useful Improvement in Portable Folding Beds, of which the following is a specification.

My invention relates to improvements in 10 folding beds and it consists in the constructions, combinations and arrangements herein described and claimed.

An object of my invention is to provide 15 a folding bed that is made in such a way that it can rapidly be taken apart; that can be rolled into a comparatively small compass; that is made of light and yet strong materials, and includes a tent cover as an accessory so that the bed may be used more 20 particularly in camping.

A further object of the invention is to provide a portable folding bed of the nature described, that can be readily carried about 25 in a conveyance, as for example an automobile, wherein it will take but little room.

A further object of the invention resides more particularly in the novel manner of holding the side rails rigid when opened, by the tension of the springs.

30 Other objects and advantages will appear in the following specification, reference being had to the accompanying drawings in which—

Figure 1 is a perspective view illustrating 35 one application of the folding bed, the mattress and tent cover being thrown back to reveal parts of the bed structure,

Fig. 2 is a perspective view of the tent observed from the rear, showing one of the 40 flaps thrown back to more clearly illustrate the means for tying them together,

Fig. 3 is a perspective view of the folding bed,

Fig. 4 is a side elevation,

Fig. 5 is a longitudinal section on the line 45 5—5 of Fig. 3,

Fig. 6 is a perspective view clearly illustrating how the tension created in the 50 springs in the setting up of the bed is subsequently employed to hold the end rails in firm engagement with the side rails,

Fig. 7 is a perspective view of the corner of the bed at the right of the observer in Fig. 6, the parts being separated to more 55 clearly illustrate their correlation,

Fig. 8 is a detail section through the joint

between one side and end rail, showing how the tension of the springs holds the two together,

Fig. 9 is a perspective view illustrating 60 the use of leather caps to cover the sharp ends of the rails,

Fig. 10 is a side elevation of a slight modification in the attachment of the legs, and

Fig. 11 is a perspective view illustrating 65 the folding bed in use in an automobile.

As has already been stated in a general way in the objects of the invention, one of the foremost uses of the bed is to provide a comfortable sleeping place for campers. As 70 a general rule, in order to lighten the burden of his equipment, a camper will carry the smallest amount of bed clothing that he thinks will suit his purpose, and will usually content himself by either improvising a bed 75 or lying directly on the ground.

Without going into detail with respect to the inconveniences of camping, or rather of attempting to sleep under such circumstances as indicated above, it may be stated 80 that these inconveniences have been attempted to be overcome by various types of folding cots. Of these there are some types that are attached to an automobile, so that when the automobile is driven to the camping 85 place, the bed is opened and thus in a sense becomes a fixture.

The herein described bed is portable in every sense of the word. Should it be taken in an automobile on a camping trip, the 90 movability of the automobile does not depend on the bed and vice versa. The bed is simply set up and inclosed by the canopy or tent cover, providing in combination a comfortable bed and a tent as well. Now dealing 95 more particularly with the construction, attention is first directed to Fig. 6 wherein the underlying principle that makes for the success of the bed, is illustrated.

The side rails 1 and 2 are divided substantially in the middle as illustrated, and pivoted together at 3. The side rails, as well as the other parts of the bed, are made of any suitable material whatever, it being preferable to make the side and end rails 100 of angle iron so as to obtain the double advantage of maximum mechanical strength 105 with minimum weight. The upper part of both side rails at each extremity has a lug 4. All of these lugs enter corresponding 110 slots 5 in the end rails 6. The four rails of the bed are thus joined or interlocked,

In fitting the parts of the bed together, one end rail 6 is laid on the ground. The side rails 1 and 2 are then bent up as shown in Fig. 6, the lugs 4 of the parts of the side rails that are laid next to the ground, being fitted into the corresponding slots 5 in the end rail just referred to. The other end rail 6 is then applied to the two upstanding side rail portions by fitting the remaining lugs 10 4 into the two slots 5.

The springs of the bed are permanently attached to the two end rails 6. These springs, spoken of in a collective sense, consist of the end coil springs 7 that join a link mattress 15 8 with the end rails. This link mattress may be of any construction suitable for the purpose. In the present instance it consists of a number of ordinary chains that are joined transversely by a number of links 9 that keep 20 the chains from spreading.

Returning now to the operation of setting up the bed. The operator holds the two side rails down in any convenient manner as by putting his feet on them and straddling the 25 link mattress. The remaining end rail is now supposed to be fitted on the upstanding side rail portions, as above mentioned, and the operator now presses down on this end rail until the side rails are straight and in the 30 correct position.

This act puts the coil springs 7 under tension. The pivots 3 are below the major axis of the link mattress and it will thus be easily understood, especially by referring to Figs. 35 4 and 5, that the greater the tension in the springs is, the more tightly will the two parts of each side rail be pressed together above the pivots. It is also to be observed that the action of the springs is in accordance with 40 the result that would take place if a person were to sit anywhere along one side rail and especially at the joint. The overlapping arrangement of one side rail on the other obtains a more rigid connection accordingly as 45 pressure is put thereon in either of the circumstances named.

A stop pin 10 with an enlarged head 11, on the inside hinged member of each side rail, fits into one or the other of two notches 50 12 in the companion member of each side rail and on the respective sides of the pivot 3. These stop pins are for the purpose of locking the members of the side rails together, either when open as in Fig. 4 or when folded 55 together for transportation.

Headed studs 13 at the extremities of the side rails, and similar headed studs 14 at the extremities of the end rails, occupy the notches 15 of the legs 16, when the legs are 60 fitted over the headed studs as shown in Fig. 5. By this means the legs are firmly fixed at the four corners of the bed when it is set up. Braces 17 permanently join the legs to the end rails 6.

65 The legs are attached to these end rails in

pairs. The braces 17 permit the legs to be swung into the folded up positions inside of the angled head rails, when they are detached from the headed studs 13. A convenient disposal of the legs is thus made when it is desired to pack the bed for transportation. 70

The use of the folding bed is not confined to the particular application pictured in Fig. 1 wherein the bed is set on the ground. The bed may be opened for use in an automobile. 75 For this purpose one pair of the legs 16 has leg extensions 18. These are normally housed inside of the legs to which they are attached, by means of a thumb screw 19. The shank of the thumb screw passes through a slot 20 80 in the companion leg, and when the thumb screw is unloosened, the leg extension can be pulled out in each case.

The end of the bed with the leg extensions is then set on the floor of the automobile, 85 while the other end of the bed whereat the legs are not extended, is rested on top of the back seat. The leg extensions 18 are long enough to support the bed over the top of the front seat. 90

Fig. 7 clearly shows how the parts of the bed are fitted together. It shows how the lug 4 at one end of a side rail is presented to a slot 5 of a head rail. The adjacent previously folded leg 16 is lifted up and set 95 upon the headed studs 13, thus locking the leg and rails together.

It is not necessary to employ the locking feature just described, *i. e.*, the arrangement of the headed studs 13 and notches 15 of the 100 legs, since the tension of the springs 7 is sufficient to hold the head pieces on the side rails under normal conditions. It is of course preferable to firmly lock the parts together, and the locking arrangement is considered 105 an ingenious method of affixing the legs and at the same time tying the corners together. However, in view of the foregoing, the headed studs 13 might be left off altogether and the legs applied in some other way. 110

This suggests the modification shown in Fig. 10. Here it will be observed that the legs 16 are attached to the side rails instead of the head rails. Use is still made of the headed studs especially in the event that the 115 legs are still fitted in the corners as indicated in full lines. However, the legs may be shifted the other way and affixed to suitable studs 39 as shown in the dotted lines. In this modification, the tension of the springs 120 7 is depended on solely to keep the head and side rails together.

A canopy 21 is intended to be used with the bed to shelter a sleeper from the elements when camping. The canopy or tent cover is 125 thrown over a central support 22. This support is hinged at a number of places so that it can be folded up and at the same time provide the end standards which are fitted in any suitable manner in openings 23 in the 130

end rails. A thumb screw 24 at each end serves to secure the standards.

Flaps 25 are provided as shown in Fig. 2. This shows the rear of the tent, but the front 5 end is just like it. The flaps are overlapped and tied together by cords 26. Obviously other fastening means can be used in place of these cords. The tent cover is arranged so that the flaps can be fastened from the 10 outside, leaving room enough for the raising of the cover so that the person may enter.

Stakes may be used to hold the tent cover down. For this purpose loops 27 are provided. However, for quickness and ease in 15 setting up and taking down the bed-tent, loops 29 are provided on the inside, to be caught over hooks 30 at corresponding places along the side rails. The use of this latter arrangement makes it easier to get into and 20 out of the tent-bed after the ends are closed. It also serves to secure the tent cover from the inside against intrusion.

A mattress 31 is carried with the outfit to be laid on the springs as shown. All of the 25 parts of the bed-tent can be rolled inside of the mattress and tent cover when taken down. In order to protect the material of the mattress and tent cover, as well as the hands and clothing of those handling the 30 bundle, the ends of the bed rail sections can be covered by cups 32 as shown in one instance in Fig. 9. These cups can be made of leather or other suitable material and are attached by a flexible connection 33.

It will be observed in Fig. 11, that one of the foremost uses of the folding bed is in 35 connection with an automobile. It has been pointed out that the bed is especially adapted for this particular use. For this one purpose, one pair of the legs are made extensible. The leg extensions 18 shown in Figs. 40 5 and 7, can be unloosened and pulled out, so that one end of the bed can be supported on the back of the rear seat, while the end 45 having the extended legs is supported on the floor of the car.

Those accustomed to making camping trips, and especially those possessing automobiles, will at once appreciate the convenience of having a folding bed that can be 50 used in this manner. The bed can be easily set up and easily taken down.

While the construction and arrangement of the folding bed is that of a generally preferred form, obviously modifications and 55 changes may be made without departing from the spirit of the invention or the scope of the claims.

I claim:—

1. The combination in a folding bed, of 60 side rails with end lugs, end rails with slots to receive the lugs, a mattress with springs attached to the end rails, to hold the lugs in the slots, adjacent projections in the corners of the end and side rails, and pivotally 65 mounted folding legs capable of being fitted over the projections to form a lock.

2. A bed, comprising a side rail member having a projection on one end, an end rail having a slot arranged to receive the projection, a link mattress including a coil 70 spring attached to the end rail and arranged to be put under tension to hold the end rail in contact with the end of the side rail member at said projection and slot connection, an 75 erectible leg attached to the end rail and arranged to be erected to provide one of the supports for the bed, and locking means associated mutually with the leg and rails, said means including headed studs on the side 80 rail member and the end rail and notches in the leg to be fitted on the studs.

3. A bed, comprising a pair of end rails with slots in the extremities, a link mattress consisting of a plurality of chains having 85 coil springs joining them at the respective ends to the end rails, transverse links joining the chains and keeping them from spreading, side rails consisting of members pivoted substantially in the middle and leaving parts to overlap when fully extended, 90 projections carried by said members arranged to be fitted in the slots of the end rails previously to extending the side rails, said springs being put under tension during 95 the act of extending the side rails thus serving to hold the bed frame together, erectible legs including braces permanently joining the legs to the bed frame, studs affixed to the bed frame to receive portions of the legs to 100 fix the legs in place, and extensible leg members carried by one pair of legs.

ROBERT H. McCUNE.
